FLIER CONSTRUCTION

Michael J. McHale, Scranton, Pa.

Application February 20, 1933, Serial No. 657,691

11 Claims. (Cl. 117—28)

This invention relates to improvements in flier blocks and more particularly to a flier block having an eccentric foot. The invention also comprehends an improved flier wire arrangement 5 adapted for use with the flier block disclosed herein and also of general application in connection with flier blocks having a peripheral wire receiving groove.

In my application Serial No. 554,664, filed Sept. 10 23, 1931, there is disclosed a removable foot for flier blocks wherein the foot is attached to the block by means of a suitable bushing or sleeve. In my application, Serial No. 554,312, filed July 31, 1931, I have disclosed an improved pre-formed 15 flier wire and securing means therefor. The present invention is an improvement over the disclosures of the above mentioned applications.

An object of my invention is to provide an improved flier block having a removable foot. 20 Another object of my invention is to provide a novel foot structure adapted to be attached to flier blocks of the type designed to be locked to a bobbin by means of a flange or foot formed on the flier block.

25 Yet another object of my invention is to provide a pre-formed wire construction, in which the wire itself forms locking means whereby the flier wire is fastened to the block.

Still another object of my invention is the provision of improved wire constructions which are adapted for mutual interlocking.

With these and other objects in view, which may be incident to my improvements, the invention consists in the parts and combinations to be 35 hereinafter set forth and claimed, with the understanding that the several necessary elements, comprising my invention, may be varied in construction, proportions and arrangement, without departing from the spirit and scope of the appended claims.

In order to make my invention more clearly understood, I have shown in the accompanying drawing means for carrying the same into practical effect, without limiting the improvements 45 in their useful applications to the particular constructions, which for the purpose of explanation, have been made the subject of illustration.

In the drawing, like numerals refer to similar parts throughout the several views, of which 50 Figure 1 is an elevational view partly in vertical section of a bobbin mounted upon a spindle and provided with a flier block and associated retaining bushing.

Fig. 2 is a perspective view of an improved flier 55 block showing the removable foot in position on the block.

Fig. 3 is a sectional view along line 3—3 of Fig. 1.

Fig. 4 is a perspective view of an improved pre-formed wire.

60 Referring to the drawing and more particu-

larly to Fig. 1, there is disclosed a bobbin 1, mounted upon a spindle 2, having an upper section 3, which is adapted to support a freely rotatable flier block 4. The bobbin is also provided with the usual bushing 5 mounted in the opening 6 formed in the upper end thereof. The flier block 4 has a central aperture 7 and is provided with a peripheral wire receiving groove 8 into which the improved flier wire 9 is fitted. The block is further provided with a peripheral groove 10 adapted to receive the foot member 11, and is tapered at 11' to facilitate positioning of the foot in the groove.

Referring to Fig. 3, the novel foot member 11 is substantially pear-shaped and is formed from 75 a single piece of wire, shaped to conform with the groove 10. The wire from which the foot is made may be of steel or other suitably hardened material of the character adapted to retain the desired shape during the operation of the flier.

The foot member is provided with an extension 12, eccentric with respect to the flier block, adapted to engage with the bobbin bushing 5 and lock the flier to the bobbin. In attaching the eccentric foot to the flier block, the wire is sprung a sufficient amount to enable it to slip over the end of the block, and seat in the groove 10. Since the foot member is formed of material which may be tensioned to give the desired spring effect, the wire will be retained in the groove during the 90 normal operation of the device. It will be noted that the wire forming the foot is not continuous and the ends 13, 14 may be sprung apart to enable the wire to pass over the lower end of the block.

While I have shown my improved eccentric foot in combination with a block designed particularly for this type of foot, it will be apparent that the improved foot is adaptable for use with conventional flier blocks.

In certain of the prior art devices, an eccentric foot formed integral with the body of the block is used. It has also been proposed to use blocks having projections of various kinds to form a foot adapted to engage with the bobbin bushing. In these devices, during the rotation of the bobbin, the block oscillates or rotates and the eccentric foot bears against the under side of the bobbin bushing and is rapidly worn down due to the comparatively small area of bearing surface. Since the eccentric foot is formed integral with the body of the block, the block must be replaced after the foot has worn away.

With my improved flier foot, it is possible to reclaim and use blocks which are initially provided with an integral foot or oppositely disposed flanges adapted for insertion into bobbins. It will be appreciated that the body of the block proper together with the wire receiving means

is generally in condition for further use after the eccentric foot has worn away.

In order to equip the discarded blocks with my improved foot, part of the original eccentric foot or flange is cut away, leaving the body of the block of uniform diameter. A peripheral groove is then formed in the body of the block near the lower end thereof, and a foot member of the type disclosed, fitted into the groove. The blocks 10 may then be applied to bobbins and are in condition for further use.

It is to be noted that the eccentric foot or flanged foot member of conventional flier blocks, is made of the same material as the blocks, usually brass. Since the bobbin bushings are of steel or other hard material, the foot member wears away rapidly with the result that the block must be replaced. My improved flier foot member is made of steel or material equally as hard 20 as the material from which the bobbin bushing is made and therefore will last longer under actual working conditions, than the conventional brass foot. When, after a continued period of use, the foot begins to wear, it may be readily replaced, thus effecting economies in maintenance of such 25 installations.

Referring to Fig. 4, I have shown an improved preformed wire adapted for use with the flier block disclosed herein and of general application 30 to flier blocks having a peripheral wire receiving groove. The flier wire comprises a single piece of wire having a drop arm 15, and straight arms 16 together with the usual eyelets 17 formed at the ends of the respective arms. The flier wire is provided with a central block engaging section 18 adapted to fit into a peripheral groove formed 35 in the block. At either side of the central block engaging sections, offset portions 20 are provided. It will be noted that these offset portions are substantially V-shape in formation and so designed to engage with each other and lock the wire to the block after the wire is positioned in the peripheral wire receiving groove.

The manner in which the wire is attached to a 45 flier block is shown in Fig. 1. The central block engaging section 18 seats in the groove 3 and arms 16 twisted or entwined so as to bring the offset portions 20 into mutual engagement and fasten the wire to the block. By providing a pre-formed wire according to the present construction, it is unnecessary to use means other than the wire itself to securely fasten the wire to the block. It will be noted that when the block and wire is in the operative position on a spindle, that the arms of the wire extend outwardly from the block in a direction opposite to the eccentric foot. This arrangement is for the purpose of providing a balanced condition of the parts during normal 50 operation of the device. In Fig. 2, it will be seen that the eccentric foot 12, fits under the flange of the bobbin bushing 5, and securely locks the flier to the bobbin.

It will be understood that the wires may be formed with offset portions of various different configurations and arranged for mutual engagement with each other when the arms are in twisted relation. The basic concept of my invention, however, is the provision of a self-locking flier wire without reference to the specific details of the offset portions or central block engaging section. It will be appreciated that while the self-locking wire is associated with a particular form of block, that the wire can be used with other blocks having a peripheral wire receiving groove.

While I have shown and described the preferred

embodiment of my invention, I wish it to be understood that I do not confine myself to the precise details of construction herein set forth, by way of illustrations, as it is apparent that many changes and variations may be made therein, by those skilled in the art, without departing from the spirit of the invention, or exceeding the scope of the appended claims.

What is claimed is:

1. A flier block for spinning machines comprising a body portion having a peripheral flier wire receiving groove and a peripheral groove to receive a foot member. 80
2. A flier block for spinning machines comprising a body portion having a peripheral wire receiving groove, a second peripheral groove spaced from said wire receiving groove, and a foot member seated in said second groove. 90
3. A flier block for spinning machines comprising a body portion having a peripheral wire receiving groove, a second groove spaced from said wire receiving groove, and a foot member formed of wire seated in said second groove. 95
4. A flier for spinning machines comprising a body portion having a peripheral flier wire receiving groove, a second groove in the body portion spaced from the wire receiving groove, and a detachable foot member seated in said second groove. 100
5. A flier for spinning machines comprising a body portion having a peripheral flier wire receiving groove, a second groove in the body portion spaced from the wire receiving groove, and a detachable foot member formed of wire and eccentric with respect to the body portion seated in said second groove. 105
6. A self-locking flier wire comprising a central block engaging section and offset portions adjacent said central section adapted for mutual engagement whereby the wire is locked to a flier block. 115
7. A self-locking flier wire comprising a central block engaging section, and substantially V-shaped offset portions adjacent said central section adapted for mutual engagement whereby the wire is locked to a flier block. 120
8. A self-locking flier wire comprising a central block engaging section, arms extending outwardly therefrom and offset portions between the arms and the central section adapted for mutual engagement whereby the wire is locked to a flier block by intertwining the arms of the flier wire. 125
9. A self-locking flier wire comprising a central block engaging section, arms extending outwardly therefrom, substantially V-shaped offset portions between the central section and the arms adapted for mutual engagement whereby the wire is locked to a flier wire by intertwining the arms of the flier wire. 130
10. An improved flier block assembly including a flier block having a peripheral wire receiving groove, and a wire fitted in said groove, said wire being provided with a central block engaging section, the arms of said wire being intertwined. 135
11. An improved flier block assembly including a flier block having a peripheral wire receiving groove, and a wire fitted in said groove, said wire being provided with a central block engaging section, and offset portions adjacent the central section, the arms of said block being intertwined and held against movement by the mutual engagement of the offset portions. 140
12. An improved flier block assembly including a flier block having a peripheral wire receiving groove, and a wire fitted in said groove, said wire being provided with a central block engaging section, and offset portions adjacent the central section, the arms of said block being intertwined and held against movement by the mutual engagement of the offset portions. 145
